(57) **CLAIM**

The ornamental design for a protecting structure and fixing buckle for notebook computer, as shown and described.

DESCRIPTION

FIG. 1 is a top, front, and right side perspective view of a protecting structure and fixing buckle for notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional perspective view taken along line 8-8 in FIG. 2; and,

FIG. 9 is a bottom, front, and right side perspective view thereof, in which the protecting structure and fixing buckle is installed on the notebook computer.

The broken lines depict portions of the protecting structure and fixing buckle for notebook computer in which the design is embodied that form no part of the claimed design. Additionally, the dot-dash lines showing a notebook computer in FIG. 9 represent environmental structure and form no part of the claimed design.
